UNITED STATES PATENT OFFICE

2,317,381

CONTAINER

John M. Hothersall, Brooklyn, N. Y., assignor to
 American Can Company, New York, N. Y., a corporation of New Jersey

Application October 6, 1939, Serial No. 298,300

1 Claim. (Cl. 229—17)

The present invention relates to containers for the packaging and delivery of liquids, such as milk, fruit juices or the like and has particular reference to sealing the closure of a sanitary fibre container.

In certain respects, the invention constitutes an improvement upon the container illustrated and described in my United States Patent 2,085,979, issued July 6, 1937, and is especially an improvement on further securing and sealing a top closure to make it tamper-proof.

The invention contemplates a liquid-proofed container which comprises a tubular body substantially square in transverse section, having flat top and bottom end members secured to the body by interfolded marginal portions constituting end seam joints in which the parts are permanently united by an interposed suitable liquid-proof adhesive to produce a leak-proof container.

An object of the invention is the provision of a tamper-proof fibre container for liquids, such as milk wherein the top end member, having a dispensing opening, is provided with a hinged plug closure which is closed and secured at the dairy by a right angled metal band of U shaped cross section embracing the marginal flange of the hinged plug closure member and the end seam joint of the container to prevent accidental opening of the closure or pilfering of the container contents without being detected by the ultimate consumer.

Numerous other objects and advantages of the invention will be apparent as it is better understood from the following description, which, taken in connection with the accompanying drawing, discloses a preferred embodiment thereof.

Referring to the drawing:

Figure 1 is a top plan view of an assembled container embodying the present invention, this view illustrating a hinged plug closure member in closed position and further sealed by a metal band;

Fig. 2 is also a view similar to Fig. 1 showing a modified form of sealing band; and

Fig. 3 is a fragmentary enlarged sectional view taken substantially along a vertical plane indicated by lines 3—3 in Fig. 1, illustrating the container parts in their sealed position.

The container illustrated in the drawing shows preferred embodiments of the invention. The drawing shows a container of the general construction described in detail in my patent hereinbefore mentioned. The container generally comprises a substantially rectangular body 11 closed at its ends with suitable top and bottom

closure members. These closure members are similar and for the purpose of this invention, only the top closure member need be illustrated. The numeral 12 designates such a top closure member.

The container body 11 is preferably formed from a single sheet of liquid-proof fibrous material folded at right angles to provide four side walls designated by the numeral 13. The edges of the sheet are joined by a lap seam extending longitudinal of the body on one of the side walls 13. Such a seam continues up and over the top bent portions of the container, being suggested in Figs. 1 and 2 of the drawing as the extended portion over the end 12 and designated by the numeral 14. This lap side seam joint is secured together by a suitable adhesive to make it liquid-proof.

The end members are substantially of the same construction and are preferably formed from the same fibrous material as the body of the container. Figure 3 of the drawing shows in detail how the top closure member 12 is interlocked with the adjacent end or marginal portion of the body. For this purpose the body marginal end portions are bent inwardly at 15 and thence outwardly as at 16 thereby providing a seat or ledge 17 which extends circumferentially of the body and upon which the closure member is supported.

The extreme edges of the body marginal portions further are bent upwardly and thence inwardly from the outer edges of the closure member to provide a spaced end flange portion 18 which extends over the margin of the closure member and seals it in place. The bent or folded parts 16, 18 of the body adjacent its end and the edges of the top closure member 12 are permanently secured together with a suitable liquid-proof adhesive. This manner of construction provides a liquid tight end seam which is indicated by numeral 19 in Fig. 3 of the drawing.

The top closure member 12 is provided with a dispensing opening 21 (Fig. 3) which is formed adjacent one corner. This opening is preferably closed with a hinge plug closure element 22 having a slightly tapered cup-shaped plug section 23. The hinge closure element 22 is secured to the top end closure member 12 as by a wire staple 24 arranged to permit the plug closure to swing rearwardly to facilitate both subsequent operations of filling and pouring or dispensing of the container contents.

As in my former patented container, the instant container is also temporarily closed by the

plug section 23 of the hinge plug closure 22 being inserted into the dispensing opening while the container is empty. This operation is preferably performed in the container manufacturers' plant so as to retain the containers in a sterile condition before and while being shipped to the dairy or packers' plant for filling and final sealing.

In order to fill the container the plug section 23 of the hinged closure is swung open on its hinged connection or staple 24 to permit filling the container through the dispensing opening 21. The filled container is then finally closed by hinging downwardly and re-inserting the plug of the plug hinged closure into the dispensing opening. The shape of the drawn plug may now be slightly altered by a suitable expanding tool to form a circumferential bead 25. This bead is pressed out of the plug section directly beneath the under side of the end closure 12 and effectively seals and locks the filled container.

Thus far the container as described is of the same construction as disclosed in my patent previously mentioned.

The filled and sealed container is now in a suitable condition for receiving the tamper-proof seal constituting the present improvement and particularly designed for the type of container described. Said tamper-proof seal element is illustrated as a right angled band of U shaped cross section and is broadly designated by the numeral 26. This band embraces the front end portion of the hinge plug closure element where the latter extends forwardly of the dispensing opening 21 as a marginal flange. This flange rests upon the end seam or joint 13 and is best illustrated in Fig. 3 of the drawing. The band is further secured while in this position by a plurality of locking tongues 27 which are or may be triangular in shape, having two adjoining sides cut from the metal band to form a tooth which is bent or struck inwardly and is imbedded in the marginal flange of the fibre hinge plug closure element, thereby more securely locking the parts together (Fig. 3).

Figure 1 of the drawing shows the marginal flange edges of the hinge plug closure element 22 as being confined in their position upon the end seam or joint therebeneath. The ends of the band, designated by numeral 28, also extend beyond the marginal closure flange and these ends 28 further directly embrace the end seam joint of the container.

Figure 2 of the drawing shows a shorter form of band eliminating the ends 28. The band 55

therefore does not extend beyond the two marginal flange edges of the hinge plug closure 22 element. Such a band, however, also covers and serves to effectively secure together the marginal flange edges of the hinged closure element and the end joint adjacent thereto.

It will be apparent from a consideration of the sealed containers illustrated by Figs. 1 and 2 of the drawing, that the metal band 26 securely retains the sealed hinge plug closure 22 in a tamper-proof condition and any pilfering of such a sealed container and any attempt to remove the band and open the closure will be easily detected and will afford visual evidence of such action.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A tamper-proof fiber container for liquids, comprising a tubular fibre body of substantially square cross section having a fibre top end member adhesively secured to an end thereof in an outwardly projecting seam joint overhanging the upper end of said body, a dispensing opening in said end member adjacent a corner thereof and a closure element hingedly secured to said end member for closing and sealing said opening, said closure element having a forwardly extending marginal flange overlying and secured to said end seam joint adjacent angularly extending portions of the latter, and a metallic sealing band of substantial channel section and angular shape embracing and secured to the localized angularly extending portions only of said seam joint by means of spaced substantially parallel inwardly projecting portions of said band respectively engaging over the marginal flange of said closure element and beneath said overhanging seam joint, said sealing band further including an integral inwardly struck tongue formed in the portion thereof engaging over the marginal flange of said closure element and penetrating said flange in locking engagement therewith, whereby to maintain said closure element in sealing position preventing unauthorized undetected opening of the container.

JOHN M. HOTHERSALL.
